(Cl. D91—3)

To all whom it may concern:

Be it known that I, Gottlob Hinderer, a citizen of the United States and a resident of the city of Los Angeles, in the county of Los Angeles and State of California, have invented a new, original, and ornamental Design for a Wall Type Swing Spout, of which the following is a specification, reference being had to the accompanying drawing, forming part thereof, in which:

Fig. 2 is a front elevation thereof; and

Fig. 3 is a side view thereof.

I claim:

The ornamental design for a wall type swing spout, substantially as shown.

GOTTLOB HINDERER.
